DESIGN FOR A PERFUME BOTTLE

Harry Jacknick, Arverne, Long Island, N. Y.

Application May 24, 1939, Serial No. 85,173

Term of patent 7 years

To all whom it may concern:

Be it known that I, Harry Jacknick, a citizen of the United States, residing at Arverne, Long Island, New York, have invented a new, original, and ornamental Design for a Perfume Bottle, of which the following is a specification, reference being had to the accompanying drawing, forming a part thereof.

Fig. 1 is a top view of a perfume bottle showing my new design.

Fig. 2 is a left side view thereof.

Fig. 3 is a front view thereof.

Fig. 4 is a right side view thereof.

Fig. 5 is a back view thereof.

I claim:

The ornamental design for a perfume bottle, as shown,

HARRY JACKNICK.
